Primary Examiner — Omeed Agilee(74) Attorney, Agent, or Firm — Holland & Hart LLP(57) CLAIM

We claim the ornamental design for a packaging container, as shown and described.

DESCRIPTION

FIG. 1 is a perspective view of a packaging container in an open configuration;

FIG. 2 is a right view thereof in an open configuration;

FIG. 3 is a left view thereof in an open configuration;

FIG. 4 is a rear view thereof in a closed configuration;

FIG. 5 is a front view thereof in a closed configuration;

FIG. 6 is a top view thereof in a closed configuration; and,

FIG. 7 is a bottom view thereof in a closed configuration. The broken lines depict portions of the packaging container that form no part of the claimed design.
